(57) **CLAIM**

The ornamental design for a ophthalmic lens, as shown and described.

DESCRIPTION

FIG. 1 is a top perspective view of the ophthalmic lens; FIG. 2 is a bottom perspective view of the ophthalmic lens; FIG. 3 is a front elevational view of the ophthalmic lens; FIG. 4 is a side elevational view of the ophthalmic lens; FIG. 5 is a top plan view of the ophthalmic lens; and, FIG. 6 is a bottom plan view of the ophthalmic lens. The broken lines in FIGS. 1,2,3,4 are for illustrative purposes only and forms no part of the claimed design.
